DESIGN FOR A CRANK

Fredrick David Chapman, Evanston, Ill., assignor to Montgomery Ward & Co., Incorporated, Chicago, Ill., a corporation of Illinois

Application October 13, 1934, Serial No. 53,611

Term of patent 7 years

To all whom it may concern:

Be it known that I, Fredrick David Chapman, a citizen of the United States, residing at Evanston, in the county of Cook and State of Illinois, have invented a new, original, and ornamental Design for a Crank, of which the following is a specification; reference being had to the accompanying drawing, forming a part hereof.

In the drawing,
Fig. 1 is a perspective view of a crank showing my new design;

Fig. 2 is a side elevation thereof; and
Fig. 3 is an edge elevation of the crank.

I claim:

The ornamental design for a crank, as shown.
FREDRICK DAVID CHAPMAN.
